HOPPER DOORFRAME

William E. Wine, Toledo, Ohio

Application May 3, 1935, Serial No. 19,737

6 Claims. (Cl. 105—253)

My invention relates to railway hopper cars and more particularly to improvements in door frames now commonly employed on such cars.

One of the objects of the invention is to provide the door frame with a lading discharge opening of increased size without enlarging the outside dimensions of the frame.

Another object of the invention is to so construct the upper portion of the frame as to increase the capacity of the hopper with which the frame is associated and to also enable the pins by which the door is hingedly connected to the frame to be so disposed as to decrease the difference in vertical height of the lower edge of the door above the tracks when the door is closed and when the door is open, to the end that the hoppers may extend a greater distance below the under frame of the car than has heretofore been possible.

The features of the invention residing in advantageous forms, combinations and relations of parts will hereinafter appear and be specifically pointed out in the claims.

In the drawings:

Figure 1 is a vertical transverse sectional view of substantially one-half of the lower portion of a railway hopper car, the door frame and door being shown in elevation.

Figure 2 is a fragmentary side elevational view of the portion of the car illustrated in Figure 1.

Figure 3 is an enlarged fragmentary sectional view taken on line 3—3 of Figure 1.

Figure 4 is a vertical sectional view taken on line 4—4 of Figure 1.

Figure 5 is an enlarged side elevational view of the lower portion of the door frame.

Figure 6 is an enlarged front view of the frame adjacent one of the lower corners thereof.

Figures 7, 8 and 9 are detail sectional views taken on lines 7—7, 8—8 and 9—9, respectively, of Figure 5.

Figure 10 is a sectional view taken on line 10—10 of Figure 6.

Referring more particularly to the drawings, 45 I indicates the center sill, the particular sill illustrated being of the integral type and including a top wall 2, and a side wall 3 which terminates at its lower edge in an outwardly projecting flange 4. The side sill of the car chosen for purposes of illustrating the invention is of conventional angle shape having a vertical flange 5 and an inwardly projecting horizontal flange 6.

Depending downwardly between the side and center sills is a hopper formed by inner and 55 outer side sheets 7 and 8, respectively, and a

downwardly inclined slope sheet 9. The main portion of the inner side sheet is preferably disposed in a substantially vertical plane, but adjacent its upper edge it inclines, as at 10, toward the center sill and terminates in a substantially vertical flange 11 secured to the adjacent side wall 3 of the latter. The outer side sheet of the hopper inclines downwardly and inwardly and adjacent its upper edge it extends outwardly at a relatively sharp angle over the horizontal flange 10 of the side sill for attachment to the vertical flange 5 of the latter. As is customary, the lower edges of the side sheets are formed with inturned flanges 12 for attachment to adjacent portions of the slope sheet 9.

Extending downwardly toward the hopper at the forward end thereof is a transversely extending floor sheet 13. At its outer edge, the floor sheet is connected to the outer side sheet 8 of the hopper by a flange 14 which is formed integrally with the latter and at its inner edge the floor sheet is connected to a splice plate 15 which joins it to the corresponding floor sheet (not shown) on the opposite side of the center sill.

Secured to the forward end of the hopper is 25 a door frame which is preferably formed as an integral casting. The frame is of substantially trapezoidal shape and it is formed with rearwardly extending side walls 16 and 17, respectively, secured to the inner and outer side sheets 30 of the hopper and with a rearwardly extending bottom wall 18 secured to the slope sheet 9. Each of these walls is formed so as to be disposed in planes corresponding to the planes of the respective sheets of the hopper to which they are attached. The frame is also provided with a top wall 19 which extends rearwardly from the forward upper edges of the side walls 16 and 17 in the same general direction as the bottom wall 18 and it serves to rigidly and effectively tie the 40 side walls together. At its inner edge, the plate-like top wall 19 is provided with an upwardly projecting flange 20 which is rigidly secured to the under side of the floor sheet 13.

The frame is provided with a substantially rectangular lading discharge opening having vertical side edges which are spaced a greater distance apart than the horizontal distance between the lower edges of the side walls 16 and 17 of the frame. Between the inclined outer side wall 17 50 and the adjacent side edge of the lading discharge opening, the frame is formed with a substantially triangular downwardly tapering front plate 21, the inner edge of which defines the side of the opening and the upper edge of the opening

is defined by a plate-like portion 22 which extends downwardly from the forward edge of the top wall 19 in the same plane as the triangular plate portion 21. The inner side and bottom edges of the opening preferably coincide with and are in effect formed by the inner and bottom walls 16 and 18, respectively.

Bounding the marginal edges of the opening are outwardly extending flanges 23 adapted to 10 cooperate with the hingedly mounted door 24 to seal the opening against the escape of lading. The flange 23 extending along the side edge of the opening adjacent the inclined outer wall 17 of the frame is disposed in a plane intersecting 15 the plane of the latter at a point, designated 25, above the bottom edge of the opening and continues downwardly in a vertical direction outside of the plane of the wall 17 where it joins the sealing flange at the bottom edge of the 20 opening. The portion of the sealing flange disposed outwardly of the outer side wall 17 is connected to the latter by a plate portion 26 which is preferably disposed in the plane of the plate portion 21 which integrally connects the inclined 25 side wall and portions of the sealing flange above the point of intersection 25. To rigidify the side of the frame where the inclined wall 17 and the adjacent sealing flange intersect, it is formed with a laterally projecting flange 27 disposed in 30 the plane of plate portions 21 and 26 and extending for some little distance above and below the point of intersection.

It will be perceived that, while this construction 35 enables the frame to be provided with a lading discharge opening of increased width, the strength of the frame adjacent the lower outer corner is not impaired, but, on the contrary, is made substantially stronger and its strength may be further increased by a flange 28 which is 40 customarily formed along the inner edge of the bottom wall 18 of the frame. This flange preferably continues upwardly along the outer side of the frame for a short distance, as indicated at 29, and on the inner side of the frame it 45 preferably extends upwardly for a considerable distance, as indicated at 30, terminating in a horizontal flange 31 for connection to the outwardly projecting flange 4 of the center sill. In addition to being connected to the center sill at this 50 point, the frame may also be secured directly to the side wall 3 thereof by providing its upper portion with a substantially vertical end flange 35.

While the sealing flange extending along the 55 upper edge of the opening is spaced downwardly from the top wall 19 to provide the front plate portion 22 which serves to render the portion of the frame above the opening extremely rigid, if it is desired to increase the vertical height of 60 the opening, the plate portion may be decreased in width so that the sealing flange forms, in effect, a prolongation of the top wall 19 in much the same way the sealing flanges along the inner 65 side and bottom of the frame constitute prolongations of the side and bottom walls.

Disposed within the angle formed by the top wall 19 of the frame and the upwardly extending flange 20 and preferably formed integrally 70 with each of these parts are a plurality of pairs of hinge lugs 32 having aligned apertures for receiving hinge pins 33 which hingedly connect the door to the frame by passing through openings formed in the upper ends of arms or straps 75 34 secured to the door. The axes of the openings

for receiving the hinge pins are spaced inwardly from the plane of the closed door, being preferably disposed closely adjacent the flange 20 secured to the floor sheet. By being able to locate the axes of the hinge pins a substantial 5 distance inwardly from the plane of the closed door, it will be perceived that, when the door is in open position, its lower edge will not extend below the lowermost edge of the hopper as great a distance as would be the case if the axes of 10 the hinge pins were disposed nearer the plane of the closed door or were located outwardly thereof. This advantageous location of the hinge pins is made possible by forming the portion of the frame above the lading discharge opening with 15 a top wall, such as wall 19, which defines or forms a part of the hopper. Not only does the top wall enable the advantageous location of the hinge pins, but it also serves, since it forms a part of the hopper, to increase the capacity 20 thereof.

Any suitable or convenient mechanism may be employed for maintaining the door in closed position, one of such mechanisms being of the hook type and including an arm 36 secured to the 25 door and projecting beyond the outer side edge thereof for cooperating with a hook 37 pivotally mounted on the outer side wall of the frame. A mechanism of this type is customarily provided with a cam 38 for locking the hook in door supporting engagement with the arm 36.

What I claim is:

1. In a railway car, the combination with a 35 hopper comprising side sheets and a slope sheet, of a floor sheet extending transversely of the car and inclined downwardly toward the hopper, a door frame having a lading discharge opening and provided with portions secured to the hopper sheets, and a door for closing the opening, the portion of the frame above the opening including 40 a flange secured to said floor sheet, a plate portion extending outwardly from the lower edge of said flange and forming a portion of the hopper, and hinge lugs disposed in the angle formed by said flange and plate portion, said hinge lugs 45 having apertures for receiving pins adapted to hingedly connect the door to the frame and the axes of said apertures being disposed inwardly of the plane of the closed door.

2. In a railway car, the combination with a 50 hopper comprising side sheets and a slope sheet, of a floor sheet extending transversely of the car and inclined downwardly toward the hopper, a door frame having a lading discharge opening and provided with portions secured to said hopper 55 sheets, and a door for closing the opening, the portion of the frame above the opening including a flange secured to said floor sheet, a plate portion extending outwardly from the flange adjacent the lower edge thereof, the outer edge of said plate portion being provided with a downwardly extending portion substantially parallel with the plane of the closed door, and hinge lugs disposed in the angle formed by said flange and plate portion, said hinge lugs having apertures adapted 60 to receive pins for hingedly connecting the door to the frame and the axes of said apertures being disposed inwardly of the plane of said downwardly extending portion.

3. In a railway car, the combination of a hop- 70 per comprising side sheets and a slope sheet, one of said side sheets being inclined downwardly and inwardly, of a door frame having walls secured to the hopper sheets and the wall thereof secured to said inclined side sheet being disposed 75

in a plane substantially parallel therewith, said frame having a substantially rectangular lading discharge opening, sealing flanges extending along the side and bottom marginal edges of the opening, the sealing flange at the bottom of the opening constituting a prolongation of the wall of the frame secured to the slope sheet and the sealing flange at the side of the opening adjacent said inclined side wall being disposed in a plane intersecting the plane of said side wall at a point spaced above the sealing flange at the bottom of the opening.

4. In a railway car, the combination of a hopper comprising side sheets and a slope sheet, one of said side sheets being inclined downwardly and inwardly, of a door frame having walls secured to the hopper sheets and the wall thereof secured to said inclined side sheet being disposed in a plane substantially parallel therewith, said frame also having a substantially rectangular lading discharge opening, sealing flanges extending along the side and bottom marginal edges of the opening, the sealing flange at the bottom of the opening constituting a prolongation of the wall of the frame secured to the slope sheet and the sealing flange at the side of the opening adjacent said inclined wall of the frame being disposed in a plane intersecting the plane of the latter at a point above the sealing flange at the bottom of the opening, and a flange projecting laterally of said inclined wall connecting portions of the sealing flange below the point of intersection with portions of said wall above the intersection.

5. In a railway car, the combination of a hopper comprising side sheets and a slope sheet, one of said side sheets being inclined downwardly and inwardly, of a door frame having walls secured to the hopper sheets and the wall thereof secured to said inclined side sheet being disposed in a plane substantially parallel therewith, said frame also

having a substantially rectangular lading discharge opening, sealing flanges extending along the side and bottom marginal edges of the opening, the sealing flange at the bottom of the opening constituting a prolongation of the wall of the frame secured to the slope sheet and the sealing flange at the side of the opening adjacent said inclined wall of the frame being disposed in a plane intersecting the plane of the latter at a point above the sealing flange at the bottom of the opening, and plate portions above and below said point of intersection integrally connecting adjacent portions of said inclined wall and the sealing flange adjacent thereto, the plate portion above the point of intersection being disposed outwardly of said sealing flange and the plate portion below the point of intersection being disposed inwardly of the sealing flange.

6. In a railway car, the combination of a hopper comprising side sheets and a slope sheet, one of said side sheets being inclined downwardly and inwardly, of a door frame having walls secured to the hopper sheets and the wall thereof secured to said inclined side sheet being disposed in a plane substantially parallel therewith, said frame having a substantially rectangular lading discharge opening, sealing flanges bounding the sides and bottom of the opening, the sealing flange at the bottom of the opening constituting a prolongation of the wall secured to the slope sheet and the sealing flange at the side of the opening adjacent said inclined wall of the frame being disposed in a plane intersecting the plane of the latter at a point above the sealing flange at the bottom of the opening, plate portions integrally connecting adjacent portions of said inclined side wall and the last named sealing flange, and a flange disposed in the plane of said plate portions projecting laterally from the frame adjacent said point of intersection.

WILLIAM E. WINE.
